ARTICLE HOLDER

Russell M. Kincaid, Detroit, Mich., assignor to
Chrysler Corporation, Detroit, Mich., a corpora-
tion of Delaware

Application July 27, 1929. Serial No. 381,619

2 Claims. (Cl. 51—205)

This invention relates to a holder and more particularly to a resilient holder for holding a plurality of objects, such as abrasive blocks used in polishing surfaces, as well as to a holder in combination with the blocks of abrasive material.

An object of the invention is to provide a device which may be easily supported in the operator's hand and preferably to make the device resilient so that it will readily conform to curved surfaces as well as to flat surfaces.

Another object of the invention is to form a holding device from a resilient material, such as a block of rubber, and to arrange a plurality of rigid projections of abrasive material on one face of the rubber.

A further object of the invention is to provide openings in one face of the holding device which overlap in horizontal planes, and to frictionally hold abrasive blocks in the openings.

Other objects and advantages of the invention will more fully appear from the following description taken in connection with the accompanying drawing, in which:

25 Fig. 1 is a side elevation of a holding block and the abrasive blocks showing a preferred embodiment of my invention, a portion thereof being broken away and in section.

Fig. 2 is a bottom view of the device shown in 30 Fig. 1, as viewed in a direction indicated by the arrows 2—2.

Referring to the drawing wherein I have illustrated a preferred embodiment of my invention, the reference numeral 10 designates a block, 35 preferably formed from rubber and is shown in rectangular formation. One face 12 of the block 10 is a plane flat surface and is provided with a plurality of recesses in the form of annular openings 14 extending only partially into the body of the block 10 forming a bottom face 16. The opposite surface 18 of the block 10 is provided with smaller openings 20 extending from the outer surface 18 to the bottom face 16.

Blocks of abrasive material 22 shown in cylindrical form are received in the larger openings 14 and seat against the bottom faces 16. The abrasive blocks 22 are longer than the depth of the openings 14 so that they project beyond the surface 12. The smaller openings 20 are for the purpose of inserting a suitable tool for punching out the remaining portion of the abrasive blocks after they have worn down flush with the surface 12 of the block 10. These openings 20 also provide a means for the escape of air in the openings 14 when the block 22 is inserted.

The edge faces 24 of the block 10 are depressed to provide a grip which makes the block easier to hold in the operator's hand.

Referring to Fig. 2, it will be seen that the abrasive blocks have been arranged in rows extending transversely of the block 10 and that the abrasive blocks 22 of one row overlap the abrasive blocks in the adjacent row when viewed in a plane parallel to the plane of the flat surface 12, and that a block in one row lies on a longitudinal line between two adjacent blocks in the row adjacent. Thus, by moving the block in any direction all portions of a surface being rubbed are covered without leaving a portion untouched.

The blocks of abrasive material 22 are preferably frictionally held in the openings 14 and when the blocks 10 are made from resilient material, such as rubber, the blocks 22 are more securely held by friction due to the elasticity of the rubber. If desired, the openings 14 may be slightly smaller than the blocks 22 to more securely hold the abrasive blocks.

When the block 10 is made of rubber it is flexible enough to permit each abrasive block to extend at right angles to the surface of the article being polished, and each abrasive block is movable independently of the other blocks. The entire device is very light in weight, thereby making it easy for the operator to support.

It will be understood that various changes, including the size, shape and material of the device, may be made without departing from the spirit of my invention and it is not my intention to limit its scope other than by the terms of the appended claims.

What I claim is:

1. A device of the class described comprising a rectangular block having a plurality of cylindrical openings in one face thereof and a plurality of smaller openings in the opposite face thereof, extending into the first named openings, and cylindrical abrasive blocks in said first named openings projecting beyond the face of the block.

2. A device of the class described comprising a rubber block having a plurality of openings in one face thereof and a plurality of smaller openings in the opposite face thereof extending into the first named openings, and abrasive blocks in said first named openings projecting beyond the face of the block.

RUSSELL M. KINCAID.
